UNITED STATES PATENT OFFICE

119,946

DESIGN FOR A SLIDE PROJECTOR

Gustav Spindler, San Francisco, Calif.

Application February 5, 1940, Serial No. 90,039

Term of patent 7 years

To all whom it may concern:

Be it known that I, Gustav Spindler, a citizen of the United States of America, residing at San Francisco, in the county of San Francisco and State of California, have invented a new, original, and ornamental Design for a Slide Projector, of which the following is a specification, reference being had to the accompanying drawing, forming a part thereof.

Figure 1 is a top plan view of a slide projector showing my new design; and

Figure 2 is a side elevational view thereof. All sides of the projector are substantially the same as the side shown.

I claim:

The ornamental design for a slide projector, substantially as shown and described.

GUSTAV SPINDLER.
